UNITED STATES PATENT OFFICE.

CHANA H. BRIGGS, OF LITTLE ROCK, ARKANSAS.

TYPE-BAR-CASTING MOLD.

Application filed February 5, 1923. Serial No. 617,126.

To all whom it may concern:

Be it known that I, CHANA H. BRIGGS, a citizen of the United States, residing at Little Rock, in the county of Pulaski and State of Arkansas, have invented certain new and useful Improvements in Type-Bar-Casting Molds; and I do hereby declare the following to be a full, clear, and exact description of the invention, such as will enable others skilled in the art to which it appertains to make and use the same.

The present invention relates to improvements in linotype molds and more particularly resides in a mold for use in producing 18 point slugs, such as used in brief work, in which italics are largely employed and wherein the lines must be double spaced to conform to the rules for printing work of this character.

20 The invention aims to enable the production of slugs containing both the primary and auxiliary faces of type from the duplex or 2-letter matrices, the slugs being 18 points high in order to permit of the proper double spacing without requiring the time consuming and laborious, as well as expensive, "leading out."

The spacing between the primary and auxiliary faces of duplex matrices does not permit the casting of the two in combination on one slug 18 points thick with the ordinary mold. The improved mold engages the mats in such a way as to cast the type faces 4 points low on the slug and this 4 points added to the ordinary 14 point slug gives the 18 point slug.

30 The advantage accruing is the setting of the matter "slugged out" and the invention obviates the process of "slugging out" subsequently and "pulling the slugs" after the printing and before dumping.

The use of the invention enables me to print law briefs spaced properly without slugging out to 18 points to the line and further enables me to use italics with roman letters, as is necessary in brief composition, while still retaining and preserving the correct alignment of the letters.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a front view of the usual form of mold.

Figure 2 is a front view of the mold constructed according to the present invention and showing the changes by comparison with Figure 1.

Figure 3 is a cross section through the old form of mold showing parts of the elevator and the mat in the lower position.

Figure 4 is a similar view showing the elevator and mat in the raised position for casting the other type face.

Figure 5 is a comparative sectional view showing the mat in the position indicated in Figure 3 but with the changes according to the present invention, and

Figure 6 is a similar sectional view comparative with respect to Figure 4 and showing the 18 point arrangement.

Referring more particularly to the drawing 1 designates generally the mold body and 2 the cap piece therefor which are fitted removably together and provide the mold cavity 3 in which the slug is cast. The molds are carried in suitable number upon the casting wheel in accordance with a well known practice and the mold cooperates with the first elevator, a portion of which is represented at 4 and which carries the mats or matrices 5 to enable the faces or die-cavities thereof to be brought into registry with one end portion of the mold cavity 3. The other end of the cavity or the end portion at the opposite edge of the mold is in communication with a source of plastic material supply which is forced into the mold cavity and into the die faces of the matrices whereby to produce the raised type upon the outer edge of the linotype slug thus cast.

A keeper 6 is carried by the mold body 1 to cooperate with the lugs 7 upon the mats 5 and the keeper is arranged below a lip 8 upon the mold body 1 which is directly below the mold cavity and extends outwardly toward the mats. A similar lip 9 is disposed upon the cap piece 2 and is a complement of the lip 8 projecting above the latter and cooperating with the elevator 4. The mat faces are designated at 10 and 11 and these may be roman and italic.

In Figure 1, end-liners 12 and 13 are shown which close the ends of the mold cavity 3. In Figure 1 the end-liners are shown to be 14 points thick or high to regulate the height of the mold cavity and the thickness or height of the slug cast.

Now in law brief work this 14 point mold is usually employed but the thickness of the slug produced is not sufficient for the 10 spacing of the lines and as a consequence the objectionable and annoying process of "leading out" or "slugging out" results. This is expensive and consumes a great deal of time. Now if it were practicable to cast 15 an 18 point slug, such slug would give the required dimension for the spacing to be secured in law brief work and would avoid this "leading out" or "slugging out" process and the expense and annoyance incident 20 thereto. This result I accomplish by the use of the mold shown in Figures 2, 5 and 6. In accordance with the invention approximately the same cap piece and mold base or body may be used and also the same 25 keeper except for a re-positioning thereof. The end-liners 14 and 15 as shown in Figure 2 are utilized, these end-liners being 18 points in height or thickness and thus increasing the height of the mold cavity suitably for producing an 18 point slug.

Now in case an attempt was made to use standard mats in conjunction with the mold structure thus varied, it would be found that the primary and auxiliary faces 35 10 and 11 of the mats would not register accurately with the central longitudinal portion of the slug and consequently the alignment of the type would be destroyed and the device useless for the purpose intended, 40 however I remedy this situation by modifying the construction of the lip 8 upon the body of the mold. This lip is shown in Figures 3 and 4 to be relatively thick but in Figures 5 and 6 in which the invention is 45 shown, a comparatively thin lip 16 is used upon the mold body 1. The reduction in thickness of this lip is not carried out upon the upper face of the lip which is required to be continuous with the bottom wall of 50 the mold cavity 3, but the entire reduction in thickness of the lip occurs at the lower portion thereof. This reduction at this particular point permits of raising the keeper 6, which is accordingly done by the use of 55 the screws 17' and the slots 18. The keeper thus undergoes a re-positioning or a raising toward the mold cavity which is permitted by the reduction in thickness of the lower portion of the lip 16 without in any wise 60 modifying the upper surface of the lip. It will thus be noted that the elevator 4 may be

required to stop only at the higher position or a position in which the upper type face or die cavity 10 is positioned centrally of the enlarged or 18 point mold cavity 3. It will 65 be found that if the usual standard type or mold useful for molding 14 point slugs is altered by grinding and reducing the lower portion of the lip upon the mold body $\frac{5}{100}$ of an inch, the mats 5 may be raised $\frac{4}{70}$ points and the type faces 10 will then arrive at a correct central position with respect to the mold cavity.

Now the invention further involves a reduction or a thinning of the upper lip 9 upon the mold cap 2. This reduced lip is shown at 17 in Figures 5 and 6. The under portion of the lip 17 is left as before to produce a proper continuation of the upper wall of the mold cavity and the reduction 80 entirely takes place from above so that we have two reduced lips 16 and 17 with proximate faces as before but with outer remote portions reduced. The reduction in the upper lip 17 is such as to permit the elevator to 85 descend as indicated in Figure 5 to bring the upper face of the mat correctly before the central part of the mold opening. In Figure 6 the lug 7 upon the mat is shown engaged with the reduced under face of the 90 lip 16 and the auxiliary face 11 of the mat 5 is shown to be in alignment with the central part of the mold cavity.

It will be appreciated that the improved mold involves no further parts over the 95 old mold and that it accomplishes the result stated simply and inexpensively while avoiding a great part of the labor and expense heretofore encountered in the printing of law briefs and the like.

100 It is obvious that various changes and modifications may be made in the details of construction and design of the above specifically described embodiment of this invention without departing from the spirit thereof, 105 such changes and modifications being restricted only by the scope of the following claim.

What is claimed is:

110 In combination with an elevator and matrices having primary and auxiliary faces carried by the elevator, said matrices having lugs, of an improved mold comprising a mold base having a thin lip, a keeper raised 115 4 points above the normal position to the thin lip, said lip cooperating with the matrices' lugs, a cap for the mold also having a thin lip to cooperate with the elevator, and end-liners of substantially 18 points between the mold base and cap.

CHANA H. BRIGGS.
